ELECTROLYTIC CONDENSER AND METHOD
OF MAKING THE SAME

Arnold Raines, Brooklyn, N. Y.

Application July 19, 1933, Serial No. 681,086

12 Claims. (Cl. 175—315)

My present invention relates to electrolytic condensers, and methods of manufacture thereof, and aims to devise a condenser of the general character specified which will be of cheaper construction than those heretofore known, and which will work at increased efficiency. Other objects and advantages of the present invention, such as simplicity, will become apparent from the embodiment of the invention shown 10 by way of example in the accompanying drawing, in which Fig. 1 shows a flat plate condenser cut away in part to show the electrolytic fluid and separating means, and Fig. 2 shows the device in coiled form.

15 Before describing in detail the elements of my present invention I wish to make a brief analysis of the prior art, from which can be seen the superiorities of my present invention. Heretofore, an electrolytic condenser has been manufactured by coating a thin strip of aluminum with a fine layer of aluminum oxide, which acts as a dielectric. Between this strip of aluminum and another strip of the same material there has been inserted a strip of absorbent fibrous material, such as gauze, which has served to prevent direct contact between the two strips of aluminum, thus preventing "shorting", and which, at the same time, has been used as a base for the electrolytic solution. In using this gauze, it has 30 been absolutely necessary to remove substantially all traces of chlorine, thus materially increasing the expense of the final product. This gauze, has, of necessity, been of a comparatively great thickness, thus increasing the amount of conducting solution used, and decreasing the efficiency of the condenser, since the electrical efficiency or power factor of the condenser is a function of the I^2R losses in the electrolyte. Furthermore, the electrical solution which has 35 been heretofore used, has, of necessity, been of a comparatively high viscosity, thus further increasing the efficiency of the condenser, because the conductivity of an electrolytic solution varies inversely with the viscosity.

40 Under my present invention, I use a non-conducting crystalline structure, shown at 4, such as common sand or finely divided alumina, which has been passed through a mesh of from about 100 to 200, this sand serving to separate the strips of aluminum or electrodes, 3. It is of course apparent that the finer the sand, the more efficient the condenser, provided of course that the electrodes are not placed so close together so as to "short".

45 On a strip of aluminum which has not been

coated with the aluminum oxide, the cathode, I sprinkle a mixture of screened sand and an oxygen liberating compound, preferably in hydrated form, whose fusing point is below the melting point of the aluminum used in the plates. I have 5 found that ammonium perborate is peculiarly well suited for this purpose. After this mixture has been sprinkled on the aluminum strip, so as to cover the strip with a thin layer thereof, I pass the strip through a furnace, heating it to a 10 temperature at which the ammonium perborate will fuse, liberating its water of crystallization, and forming a film-like coating in which the sand is embedded and affixed to the aluminum strip. I then apply to this strip, as treated, a film-like 15 conducting solution, such as a mixture of ammonium borate and ethylene glycol, the ammonium borate constituting about 10% to 60% of the solution, by weight. I then place this strip in juxtaposition to the strip coated with the 20 aluminum oxide, and assemble in the usual manner, 5 and 6 showing the terminals of the condenser in assembled form.

I have found that by using this crystalline material, I have been enabled greatly to decrease the space between the two aluminum strips, without fear or danger of "shorting", and, at the same time, it has been possible to use a much less viscous conducting solution, without the likelihood of the fluid running off in subsequent operation and use.

25 While I do not wish to be bound by my present explanation of why I am enabled to use a thinner solution, I believe that the film-like coating of fused ammonium perborate absorbs some portion at least of the solution, preventing it from 30 running off.

35 Since it is apparent that the efficiency of a condenser varies inversely with the amount of conducting solution between the plates per unit 40 area of plate surface, one advantage of my present invention is obvious. Furthermore, because of the fact that the conducting solution will not run off, even though comparatively thin, I am 45 enabled to use a conducting solution of optimum viscosity, that is, that viscosity at which the solution offers the least resistance to the passage of an electric current. Furthermore, since the losses which result in a condenser of lessened efficiency are transmuted largely into heat, which 50 heat tends to decrease the resistance of, and finally break down the coating of aluminum oxide, a further advantage of my present invention is the longer life of a condenser made in accordance therewith.

This completes the description of the illustrative embodiment of the present invention. The foregoing is only illustrative and descriptive, and it may readily be seen that numerous changes and modifications may be made without departing either from the principle and spirit of the invention or the scope of the claims. For example, instead of ammonium perborate I can use boric acid or any borate whose fusing point is lower than the melting point of the electrode, and in fact any oxygen liberating compound which will fuse at a lower temperature than the melting point of aluminum. Furthermore, instead of sand or alumina, I can use any finely divided highly insulating crystal.

What I claim as my invention is:

1. An electrolytic condenser composed of a plurality of electrodes, at least one of which is film-forming, said electrodes being separated by finely divided non-conducting crystals affixed to one of the electrodes.
2. An electrolytic condenser composed of a plurality of electrodes, at least one of which is film-forming, said electrodes being separated by finely divided non-conducting crystals which are fused to one of the electrodes by an oxygen liberating compound.
3. An electrolytic condenser composed of a plurality of electrodes, at least one of which is film-forming, said electrodes being separated by finely divided sand affixed to one of the electrodes.
4. An electrolytic condenser composed of a plurality of electrodes, at least one of which is film-forming, said electrodes being separated by finely divided sand which is fused to one of the electrodes by ammonium perborate.
5. An electrolytic condenser, composed of a plurality of electrodes, at least one of which is film forming, said electrodes being separated by finely divided non-conducting crystals which are embedded in a fused salt affixed to one of the electrodes.
6. In an electrolytic condenser composed of a plurality of electrodes, at least one of which is film-forming, an electrode, the surface of which is provided with finely divided non-conducting crystals which are embedded in a fused salt affixed to one of the electrodes.

7. In an electrolytic condenser composed of a plurality of electrodes, at least one of which is film-forming, an electrode, the surface of which is provided with finely divided non-conducting crystals which are embedded in a fused oxygen liberating compound affixed to one of the electrodes.

8. In the process of making an electrolytic condenser, the steps of applying finely divided non-conducting crystals and an oxygen liberating compound to one of the electrodes, and thereafter fusing said oxygen liberating compound so that the finely divided non-conducting crystals are embedded in the resulting fused oxygen liberating compound.

9. In the process of making an electrolytic condenser, the steps of applying finely divided sand and an oxygen liberating compound to one of the electrodes, and thereafter fusing said oxygen liberating compound so that the finely divided sand is embedded in the resulting fused oxygen liberating compound.

10. In the process of making an electrolytic condenser, the steps of applying finely divided non-conducting crystals and ammonium perborate to one of the electrodes, and thereafter fusing said ammonium perborate so that the finely divided non-conducting crystals are embedded in the resulting fused ammonium perborate.

11. In the process of making an electrolytic condenser, the steps of applying finely divided sand and ammonium perborate to one of the electrodes, and thereafter fusing said ammonium perborate so that the finely divided sand is embedded in the resulting fused ammonium perborate.

12. In the process of making an electrolytic condenser, the steps of applying finely divided non-conducting crystals, and an oxygen liberating compound whose fusing point is lower than the melting point of the electrodes, to one of the electrodes, and thereafter fusing said oxygen liberating compound so that the finely divided non-conducting crystals are embedded in the resulting fused oxygen liberating compound.

ARNOLD RAINES.
